(No Model.)

I. DE HAVEN.
COOKING STOVE.

No. 431,255.

Patented July 1, 1890.

FIG.1.

FIG.2.

FIG.3.

FIG.4.

UNITED STATES PATENT OFFICE.

ISAAC DE HAVEN, OF ALLEGHENY, PENNSYLVANIA.

COOKING-STOVE.

SPECIFICATION forming part of Letters Patent No. 431,255, dated July 1, 1890.

Application filed May 2, 1887. Serial No. 236,817. (No model.)

To all whom it may concern:

Be it known that I, ISAAC DE HAVEN, residing at Allegheny, in the county of Allegheny and State of Pennsylvania, a citizen 5 of the United States, have invented or discovered a certain new and useful Improvement in Cooking-Stoves, of which improvement the following is a specification.

My invention relates to outside shelves for 10 the ovens of cook stoves and ranges; and its object is to enable the shelf to be readily attached to and detached from the stove, as from time to time required, and to be held truly and firmly when fixed in position 15 thereon.

To this end my invention, generally stated, consists in the combination, with a side plate having two or more slotted lugs adjacent to its lower end, of an outside shelf having a 20 vertical flange or projection on its inner face adapted to engage the lugs of the side plate.

The improvement claimed is hereinafter fully set forth.

In the accompanying drawings, Figure 1 is 25 a view, in perspective, of a cooking-stove with my improvement applied. Fig. 2 is a similar view, on an enlarged scale, of the lower portion of the side plate detached; Fig. 3, a similar view of the outside shelf, looking 30 from below, and Fig. 4 a transverse section, on an enlarged scale, through the same.

As heretofore constructed, the outside shelves, used for sustaining articles taken from the ovens of stoves and ranges, have 35 been connected to the side plates of the same by nuts screwed upon bolts passing through the plate and shelf, such construction involving the objections of expense in fitting and liability of the shelf to sag, work loose, and 40 become detached. A removable outside shelf has also been proposed having hook-shaped lugs at top fitting in ears on the side plate of the stove, and feet or legs resting in grooves in the bottom moldings or ledges of the stove, 45 a shelf of this character being a correspondingly heavier and more expensive casting than the ordinary shelves which are bolted on, as above stated. These objections are avoided under my invention, in the practice 50 of which I cast in line upon the outer face of the side plate 1, which forms an outer boundary of the oven, near its lower end and shortly below the desired level of the top

of the shelf, two or more lugs or projections 2, each of which is reduced in width at and 55 adjoining the plate 1 by a slot or recess 3. A vertical flange or projection 4 is cast upon and flush with the inner side of the outside shelf 5, said flange projecting below the lower side of the shelf and providing a broad 60 bearing for the same against the side plate 1, by which tendency to sagging or rocking is prevented. In order to prevent longitudinal movement of the shelf, slots or recesses 6, of proper width to fit easily over the narrow or slotted portions of the lugs 2 of the side plate, are preferably formed in the flange 4, said slots corresponding in number and relative location with the lugs 2. Two or 65 more vertical brackets 7, the faces of which 70 are in line with the inner face of the shelf, serve to afford additional bearing-surface on the side plate, and, if desired, the flange 4 may be dispensed with at points other than adjacent to the lugs 2, so that substantially 75 all the bearing may be given by the vertical faces of the brackets 7.

It will be seen that the outside shelf may be readily and conveniently attached to or 80 detached from the side plate by a simple vertical movement, and when connected thereto will be firmly held in position as against any tendency to sag or become loose or to accidental displacement.

I disclaim, broadly, a removable outside 85 shelf as well as a shelf of such character which is connected by hooked lugs to ears on the side plate of the stove and is supported by legs resting upon a bottom molding or ledge.

I claim as my invention and desire to secure by Letters Patent—

The combination, in a cooking stove or range, of a side plate provided with laterally-slotted lugs, and an outside shelf which is provided with a vertical flange or projection 95 on its inner side, having recesses adapted to engage the narrow or slotted portions of the lugs of the side plate, and vertical-faced brackets adapted to abut against said plate, substantially as set forth.

In testimony whereof I have hereunto set my hand.

ISAAC DE HAVEN.
